UNITED STATES PATENT OFFICE.

STANLEY O. HASKINS, OF CHATTANOOGA, TENNESSEE, ASSIGNOR OF ONE-HALF TO L. W. LLEWELLYN AND J. E. EVANS, OF SAME PLACE.

NUT-LOCK.

SPECIFICATION forming part of Letters Patent No. 599,448, dated February 22, 1898.

Application filed April 24, 1897. Serial No. 633,742. (No model.)

To all whom it may concern:

Be it known that I, STANLEY O. HASKINS, a citizen of the United States, residing at Chattanooga, in the county of Hamilton and State 5 of Tennessee, have invented a new and useful Nut-Lock, of which the following is a specification.

The invention relates to improvements in nut-locks.

10 The object of the present invention is to improve the construction of nut-locks and to provide a simple, inexpensive, and efficient one adapted to be readily applied to single nuts to lock them securely against accidental 15 unscrewing and capable of enabling a nut to be readily removed when desired.

A further object of the invention is to provide a nut-lock which will be capable of expanding to hold a nut perfectly tight should 20 the head of a bolt settle slightly.

The invention consists in the construction and novel combination and arrangement of parts hereinafter fully described, illustrated 25 in the accompanying drawings, and pointed out in the claim hereto appended.

In the drawings, Figure 1 is a perspective view of a nut-lock constructed in accordance with this invention and applied to a rail-joint. Fig. 2 is a horizontal sectional view. Fig. 3 30 is a detail perspective view of the attachment-plate. Fig. 4 is a similar view of the locking-plate.

Like numerals of reference designate corresponding parts in all the figures of the drawings.

35 1 designates an attachment-plate constructed of resilient metal, provided with a bolt-opening and interposed between the inner face of a nut 2 and a fish-plate 3, and it is 40 corrugated in order that it may be compressed when the nut is screwed on its bolt 4, whereby the attachment-plate is adapted to expand and hold the nut perfectly tight should the head of the bolt settle slightly, as is often the 45 case.

The attachment-plate is slit or cut longitudinally at one end at opposite sides of the center, forming a central tongue 5 and side 50 tongues 6, arranged above and below the central tongue. The central tongue, which is adapted to engage a locking-plate 7, extends

through an opening 8 thereof and is bent substantially V-shaped in order to embrace partially a pintle 9, which is formed by the opening 8. The opening 8, which is disposed adjacent to one end of the locking-plate, leaves the narrow strip or pintle portion 9 to be engaged by the central tongue, as above set forth. The side tongues extend outward slightly and engage the outer edge of the locking-plate with sufficient spring to hold the locking-plate firmly in engagement with the nut. The locking-plate is provided at its engaging edge with a V-shaped recess 10, arranged to receive one corner of the nut and engage two of the side faces thereof, whereby the nut is firmly held against accidental unscrewing. When it is desired to remove the nut, the locking-plate is swung outward. The spring-tongues 6 hold the pintle portion of the locking-plate in the bend of the central tongue and prevent the locking-plate from becoming accidentally detached from the attachment-plate.

Although the nut-lock is shown applied to a portion of the rail-joint, yet it is applicable to various constructions and machinery where it is desirable to prevent a nut from accidentally unscrewing.

The corrugations of the attachment-plate, 80 besides serving to hold the nut tight, also operate to offset the side tongues from the fish-plate and increase the resiliency of the hinged joint. When the locking-plate is swung away from the nut, the side tongues and the central tongue yield and all of the strain is not centered on the central tongue 5, as would be the case were the attachment-plate perfectly straight and arranged flat against the fish-plate. The corrugations also serve another 85 useful purpose and render the nut-lock adjustable to fit nuts varying slightly in size. By screwing a nut tightly against the corrugated attachment-plate the latter is expanded and lengthened and will enable the locking-plate to engage a nut slightly larger than it could were the corrugated plate not compressed to such a degree.

90 It will be seen that the nut-lock is simple and comparatively inexpensive in construction, that it is positive and reliable in operation and capable of effectually preventing a

nut from accidentally unscrewing, and that it will permit a nut to be readily removed without impairing it. It will also be seen that the corrugated plate is adapted to be compressed when the nut is screwed on the bolt and that it will expand and hold the nut perfectly tight should the head of the bolt settle slightly.

What I claim is—

- 10 A nut-lock comprising a locking-plate provided with an opening forming a pintle, and an attachment-plate constructed of resilient material, provided with a bolt-opening and split longitudinally at opposite sides of the
- 15 center, forming central and side tongues, the central tongue extending through the open-

ing of the locking-plate and the side tongues engaging the outer edge of the latter to form a hinge-joint, said attachment-plate being corrugated and increasing the resiliency of 20 the hinge-joint and capable of compression, whereby it is lengthened to enable the locking-plate to engage nuts varying slightly in size, substantially as described.

In testimony that I claim the foregoing as 25 my own I have hereto affixed my signature in the presence of two witnesses.

STANLEY O. HASKINS.
